CLAIM

The ornamental design for a fluid container, as shown and described.

DESCRIPTION

FIG. 1 is a front elevational closed view of a fluid container showing our new design;

FIG. 2 is a reduced scale front elevational partially open view thereof;

FIG. 3 is a reduced scale front elevational fully open view thereof;

FIG. 4 is a left side elevational closed view thereof;

FIG. 5 is a reduced scale left side elevational partially open view thereof;

FIG. 6 is a reduced scale alternative left side elevational fully open view thereof;

FIG. 7 is a right side elevational closed view thereof;

FIG. 8 is a reduced scale right side elevational partially open view thereof;

FIG. 9 is a reduced scale right side elevational fully open view thereof;

FIG. 10 is a rear elevational closed view thereof;

FIG. 11 is a reduced scale rear elevational partially open view thereof;

FIG. 12 is a reduced scale rear elevational fully open view thereof;

FIG. 13 is an enlarged top plan closed view thereof;

FIG. 14 is a top plan partially open view thereof;

FIG. 15 is a reduced scale top plan fully open view thereof;

FIG. 16 is a bottom plan closed view thereof;

FIG. 17 is a reduced scale alternative bottom plan partially open view thereof;

FIG. 18 is a reduced scale alternative bottom plan fully open view thereof;

FIG. 19 is a front perspective closed view thereof;

FIG. 20 is a front perspective partially open view thereof; and,

FIG. 21 is a reduced scale front perspective fully open view thereof.
